UNITED STATES PATENT OFFICE.

LLOYD F. LAYNE, OF HOUSTON, TEXAS, ASSIGNOR TO LAYNE & BOWLER COMPANY, A CORPORATION OF TEXAS.

WELL-SCREEN.

1,335,975.

Specification of Letters Patent. Patented Apr. 6, 1920.

Application filed October 23, 1916. Serial No. 127,053.

To all whom it may concern:

Be it known that I, LLOYD F. LAYNE, a citizen of the United States, residing at Houston, in the county of Harris and State of Texas, have invented certain new and useful Improvements in Well-Screens, of which the following is a specification.

This invention relates to well screens and it has reference primarily to that form of well screen apparatus in which a perforated or foraminous well tubing is employed about which is wrapped the wire which constitutes the screening element. This form of well screen is used in water or oil wells where the soil is sandy and its purpose is to permit a free flow of water into the interior of the well tubing while at the same time foreign matter is effectually excluded.

One of the principal objects of the invention is to provide a novel and simple form of well screen in which the screening wire may be simply and expeditiously put in place and is securely maintained in position.

The foregoing, together with such other objects as may hereinafter appear or are incident to my invention I attain by means of the invention which is illustrated in the accompanying drawing in which the figure 30 is a partial side elevation and partial section of the well tubing, showing the application thereto of the screening wire also in side elevation and in section. The process of manufacture will be understood from a 35 description of the screen.

Referring now to the drawing, I have shown a well tubing or frame 7 such tubing or frame being provided with a plurality of perforations, orifices or open spaces 8 by means of which the water or oil is carried into the interior of the tubing forming the well chamber. The well tubing is provided with an exterior helical groove 9, or, stated in another way, the well tubing is 45 threaded, the preferred form of thread being square as shown in the upper portion of the figure in side elevation. The form of the screening wire which I prefer to employ is of that general type which may best 50 be described by stating that in cross section it is substantially in the form of a truncated pyramid which is wound upon the tubing with the small end in the groove or thread. The wire 10 shown in the drawing, while 55 of the general type just described, is a de-

parture from the wire heretofore employed in that the thin or small end of the wire 10^a is slightly offset or bent so that the wire in cross section is irregular at its inner edge, for a purpose which will hereinafter appear. 60 The wire is shown in cross section in the lower half of the figure.

After the tubing has been threaded or grooved, the wire 10 is wound thereon in the form of a helix by any preferred type of 65 wire winding machine, the wire being fed from the machine into the groove by rotating the tubing. Up to this point the wire is arranged in the groove in the manner indicated in that portion of the cross sec- 70 tion of the screen marked *a*.

In order to secure the wire in position in the groove, a suitably supported compressing tool is inserted into the space formed in the helix of the wire, which tool preferably consists of a disk 11 rotatably mounted on the support 12 and which extends angularly into said space to engage the outer face of the thread at a point adjacent the lower face of the wire. As the casing is rotated, the disk 11 crowds the metal of the thread against the lower face of the wire, wedging the metal tightly about the wire, whereby the wire, because of its irregular cross-sectional form, is securely fastened in 85 position. The manner in which the tool operates to compress the metal and lock the wire is clearly shown in the lower portion of the figure.

As a completed article of manufacture, 90 the screen consists of a perforate tubing about which is wound a helix of screening wire providing a substantially continuous annular channel on the exterior of the tubing, which channel is larger at the base 95 next to the tubing than at the exterior edges of the wire. The screen thus excludes foreign matter while at the same time there is provided a relatively large circulating channel by means of which the liquid is rapidly 100 and freely conducted into the interior of the well tubing through the perforations. The space between adjacent edges of the screening wire is determined by the width of the groove, or, stated in another way, by 105 the thickness of the thread on the tubing or different width of wire. By modifying the size of the groove, the screening area of the wire is modified so as to meet the service conditions of the particular field of use. 110

It will be apparent that the method of making the screen is simple and can be expeditiously carried out and that the resultant product is of a superior quality, particularly with respect to the secure manner in which the wire is fastened in position.

It will be understood, of course, that the specific form of the well tubing or frame may be changed without departing from the spirit of this invention. Other advantages will occur to those familiar with the art.

I claim:

1. As a new article of manufacture a well screen comprising a well tubing provided with a plurality of apertures therein and having formed in its outer face a square thread, a helix of screening wire seated in the groove between the turns of the said thread, said wire being substantially rectangular in cross-section and having an angular depression formed in one lateral face thereof to provide a portion adjacent to the base of the wire of less thickness than the base, said wire being held in position by

compressing the metal of the thread into 25 said depression.

2. As a new article of manufacture a well screen comprising a well tubing provided with a plurality of apertures therein and having formed in its outer face a square 30 thread, a helix of screening wire seated in the groove between the turns of the said thread, said wire being substantially rectangular in cross-section and having an angular depression formed in one lateral face 35 thereof to provide a portion adjacent to the base of the wire of less thickness than the base, said wire being held in position by compressing the metal of the thread into said depression throughout the length of the 40 helix.

In testimony whereof I have hereunto signed my name.

LLOYD F. LAYNE.
